MULTIPLE COMPRESSION CONNECTOR

John J. Klosin, New Brunswick, N. J., assignor to The Thomas & Betts Co., Elizabeth, N. J., a corporation of New Jersey

Application December 2, 1957, Serial No. 48,734

Term of patent 14 years

(Cl. D26—1)

Fig. 2.

Fig. 1 is a view in perspective of the multiple compression connector showing my new design; and

Fig. 2 is a view in elevation, partly in section, showing the same.

The opposite sides and end faces of the multiple compression connector not shown are substantially mirror images of those shown.

I claim:

The ornamental design for a multiple compression connector, as shown and described.
